EXTENSION HINGE

Robert W. Banks, Memphis, Tenn.

Application April 16, 1937, Serial No. 137,336

4 Claims. (Cl. 16—163)

This invention relates to extension or offset hinges which are especially adapted for hanging windows, doors, and the like.

One of the important objects of this invention 5 is the production of a simple and efficient hinge which will facilitate the swinging outwardly of the window or door supported thereby, in a manner whereby the window or door may be swung beyond the frame or may be reversed for the 10 purpose of facilitating the washing, painting, and the like, of the outside face of the window, door, sash or panel.

A further object of this invention is the production of a simple and efficient hinge for supporting a window sash and the like, in such a 15 manner as to permit the maximum amount of air and light to enter through a window and also to permit the positioning of a sash in a manner to prevent a direct draft from passing through 20 a window.

Other objects and advantages will appear throughout the following specification and claims.

In the drawings:

Figure 1 is a front elevation of a window frame 25 illustrating one type of sash with which my improved hinge is used;

Figure 2 is a horizontal sectional view taken on line 2—2 of Figure 1;

Figure 3 is an enlarged front elevation of a 30 portion of a sash showing my improved hinge applied thereto, certain parts being shown in section;

Figure 4 is a horizontal sectional view taken on line 4—4 of Figure 3;

Figure 5 is a horizontal sectional view taken 35 on line 5—5 of Figure 3, with the panel swung outwardly;

Figure 6 is a horizontal sectional view through the sash showing the hinge in an extension position and the panel swung back over the window frame;

Figure 7 is a vertical sectional view taken on line 7—7 of Figure 3;

Figure 8 is a sectional perspective view of one 45 corner of the sash and panel carried thereby;

Figure 9 is a sectional perspective view of one corner of the sash and panel, the panel being swung to an extended position;

Figure 10 is a perspective view of the hinge 50 showing one face thereof;

Figure 11 is a perspective view of the hinge showing the other face thereof;

Figure 12 is a sectional perspective view of one 55 corner of a sash and panel, showing a modified type of hinge mounting;

Figure 13 is a sectional perspective view of a corner of a sash and panel showing a modified form of hinge;

Figure 14 is a perspective view of the type of 60 hinge illustrated in Figure 13;

Figure 15 is a sectional perspective view of one corner of a sash and panel, showing a further modified type of hinge mounting;

Figure 16 is a perspective view of a sash and panel showing a still further modified form of 5 hinge structure;

Figure 17 is a perspective view of a sash and panel, showing the panel swung to an open position;

Figure 18 is a perspective view of a sash and 10 panel showing the same as applied to a casement window.

By referring to the drawings, it will be seen that A designates the window frame in which frame A are slidably mounted the sashes 10 and 11 in the conventional manner, a suitable latching means 12 being employed for locking the sashes together. Each sash supports panels 13 and 14 which fit within the openings 15 of the sashes. These panels 13 and 14 may be held in a closed 20 position by means of suitable latches 16. Weather strips 17 may also extend over the adjoining edges of the panels 13 and 14 and the sashes 10 and 11 to constitute a seal therefor, if desired, the weather strips 17 being notched, as at 18, 25 near their respective ends to permit the supporting hinges, hereinafter described, for the panels 13 and 14 to operate.

Each panel 13 and 14 is supported by a pair of specially constructed hinges designated generally by the letter B, and these hinges are similarly constructed. Each hinge B comprises an elongated anchoring plate 19 which is preferably inset within a socket 20 of the rail of the sash upon which the hinge is mounted, the plate 19 30 of the upper sash being inset to extend flush with the under side of the upper rail of the sash and the plate 19 of the lower hinge being inset to extend flush with the upper face of the lower rail of the sash, as clearly illustrated in Figure 35 3. The plate 19 in each instance is suitably anchored upon the sash by means of suitable screws 21 which are countersunk, as shown.

An extension arm 22 is pivotally secured, as at 40 23, to one face of the anchoring plate 19 by 45 means of a counter-sunk rivet, the extension plate or arm 22 of the upper hinge being secured to the under face of the anchoring plate 19 and the extension arm or plate 22 of the lower hinge being secured to the upper face of the anchoring 50 plate 19, as shown in Figure 3. A pintle pin 24 is secured to the extension arm 22 at one end, as shown clearly in Figure 10, the pin being riveted or otherwise secured to the arm 22 and being adapted to receive the barrel of the hinge plate 55 25, which hinge plate 25 is secured in any suitable manner to one edge of one of the panels 13 or 14. The hinge plate 25 is preferably fitted within the recesses formed in the side edges of the panels 13 and 14 which abut the sides of the sashes 60

10 and 11. The pintle pins 24 are preferably provided with suitable heads for holding the barrel portions of the hinge plates 25 upon the pintle pins 24.

- 5 Each extension arm or plate 22 is provided with a substantially U-shaped notch 27 which is adapted to receive a tongue 28 of the clutch plate 29, which clutch plate 29 is slidably mounted upon the anchoring plate 19, in the manner as 10 shown in Figure 10, and in a position to cause the tongue 28 to register with and fit into the U-shaped notch 27. The clutch plate 29 is secured to the anchoring plate 19 by means of a screw 30 which extends through an elongated slot 31 15 formed in the clutch plate 29, the head of the screw 30 being counter-sunk to extend flush with the plate 29.

In mounting the hinge, the sash 13, such as is 20 shown in Figure 3, is provided with a socket 32 upon its upper and lower faces of the thickness of the clutch plate 29 and extension arm 22 in a manner to allow the hinge to be folded in a position to cause the edge of the hinge to extend flush with the outer face of the supporting panel 25 when the hinge is in a closed position such as is 25 shown in Figure 5. The notch 31 is of sufficient length to allow the clutch plate 29 to be moved to and from a locking position. All of the hinges are similarly constructed in the forms shown in 30 Figures 1 to 11, inclusive, and when mounted upon the respective panels of the respective sashes the pintle pin 24 of the upper hinge extends downwardly and the pintle pin 24 of the lower hinge extends upwardly, as is clearly shown in Figures 35 1 and 3. It should be understood that both the upper and lower hinges are similarly constructed, but only their positions are reversed.

By carefully considering Figures 4, 5 and 6, the 40 operation of the device will be clearly understood. The panel 13 for example, may be swung outwardly with respect to the sash 10 upon the pintle pins 24 of the hinges B, if it is merely desired to swing the panels to an open position at right angles to the sash 10. If it is desired, however, 45 to throw the panel 13 to a position where it will lie back over the frame A, the clutch plate 29 may be moved to the position shown in Figure 6, drawing the tongue 28 out of the notch 27 and allowing the extension plate or arm 22 to pivot 50 upon its pivot 23 and move to a position at right angles to the anchoring plate 19, moving the sash 13 in spaced relation with respect to the frame A and to a position substantially parallel to the sash 10, as is shown in Figure 6. By means of 55 this particular type of hinge, it will be seen that the panels 13 and 14 may be swung open to a position at substantially right angles to the sash 10 or by releasing the clutching plate 29 the sashes may be swung to a position substantially 60 parallel to the supporting sash or to a position as shown in Figure 6. As is clearly shown in Figure 8, when the panel, such for instance as the panel 13, is in a closed position upon the sash 10, the hinge will be completely shielded or 65 housed between the panel and the sash and the moving parts are so positioned as to extend flush with the abutting faces of the panels and sash allowing the panels and sash to snugly fit with 70 respect to each other. Where weather stripping, such as is shown in Figures 1, 2 and 3, is used, it is important that the inner edge of the stripping be in line with the center of the pintle pin so that the sash may be swung open sufficiently to allow the clutch plate to be operated 75

for the purpose of throwing the sash to a position such as is shown in Figure 6.

From the foregoing description it will be seen that a very simple and efficient means has been provided for supporting the hinged panels 13 and 14 upon the sashes 10 and 11 so as to allow the sashes to slide over each other when raising and lowering the same. It should be further understood that the clutching plate 29 will rigidly lock the extension arm 22 in position until the clutching plate is released so that the device will act as a conventional hinge while the clutching plate 29 is in a locking position and will act as an extension hinge when the clutching plate is released to an unlocking position such as is shown in Figure 6.

In Figure 12 there is shown a modified type of the invention wherein a sash 32^a is illustrated carrying a panel 33. An anchoring plate 34 is secured to one face of the sash 35 by means of the lugs or ears 36, the plate 34 extending laterally at substantially right angles to the outer face of the sash 32^a. An extension plate 37 is pivotally secured, as at 38, to the upper face of the plate 34 and carries a pintle pin 39 which 25 engages a hinge plate 40 secured to the outer face of the panel 33, as shown in Figure 12. The extension plate 37 is provided with a notch 41 for receiving the tongue 42 of the slidably mounted clutch plate 43 which clutch plate 43 is slidably 30 mounted upon the anchoring plate 34, as shown in Figure 12. The hinge shown in Figure 12 operates in a manner similar to that as shown in Figures 1 to 11 inclusive, with the exception that the structure shown in Figure 12 is secured to 35 one face of the sash 32^a and panel 33 and is not counter-sunk or inset as is the case with the previously described form.

In Figures 13 and 14, I have shown a further modified form of the invention, wherein 44 indicates the sash which is provided with a weather strip 45, notched as at 46. A panel 47 is mounted within the sash 44 and is notched, as at 48, for receiving the hinge plate 49, which hinge plate 49 is engaged by a pintle pin 50 carried by the outer 45 end of a pivoted link 51, which pivoted link 51 is pivoted, as at 52, to the anchoring plate 53. The anchoring plate 53 is inset within the socket 54 formed in the sash 44, and the link 51 is inset within a socket 55 formed in the abutting face 50 of the panel 47. In the form shown in Figures 13 and 14, the extension arm 51 is pivoted to the anchoring plate 53 and no clutching device is provided, the extension arm 51 being free to allow the panel 47 to swing outwardly and away 55 from the side of the sash 44, as the panel 47 is swung outwardly.

In Figure 15 there is shown a further modified form of my invention, wherein 56 indicates a sash which carries a panel 57. An anchoring 60 plate 58 is secured to the inner face of the sash 56 and extends at right angles thereto. The panel 57 carries a hinge plate 59 which engages a pintle pin 60 carried by the outer end of the extension plate 61, which extension plate 61 is pivotally secured, as at 62, to the anchoring plate 58, as shown in Figure 15. The inner end of the extension plate or arm 61 is notched, as at 63, and is adapted to be engaged by the tongue 64 of the sliding clutch plate 65 which is similar to the clutch plate 29 previously described. The anchoring plate 58 in the form shown in Figure 15 is preferably counter-sunk or inset within the sash 56 so as to extend flush therewith and to 75

allow the panel 57 to fit snugly in position when closed.

As shown in Figure 16 and Figure 17, there is illustrated a further modified form of the invention. In this form a sash 70 is illustrated which supports a panel 71, the panel 71 carrying hinge plates 72 at its upper and lower inner corners, which hinge plates 72 are pivotally connected to the outer ends of the extension links 73, which links 73 are pivoted, as at 74, to the inner face of the sash 70 at a point approximately in the center thereof. The panel 71 is preferably notched, as at 75, upon its upper and lower faces to allow the extension links or arms 73 to snugly fit between the panel 71 and the sash 70. In the form shown in Figure 17, it will be seen that the panel 71 may be swung to the position shown in full lines in Figure 17 at substantially right angles to the sash 70, or may be swung to either of the two dotted positions, allowing free and easy access to either the inner or the outer faces of the panel 71 for the purpose of washing the glass plane, or painting or cleaning the panel.

In Figure 18 there is shown a still further modified form of the invention as applied to a casement window, wherein a sash 76 is illustrated in which is mounted a panel 77 which is pivotally connected at its upper and lower inner corners to the outer ends of the upper and lower links 78 and 79 respectively. Each link 78 and 79 is in turn pivotally connected at its inner end to a suitable bracket 80 secured to the inner face of the sash 76 near its center, in this way allowing the panel 77 to be swung to a position substantially at right angles to the sash 76 or to an offset position substantially parallel to the sash 76, either to the right or to the left, as shown in dotted lines in Figure 18.

From the foregoing description it will be seen that a very simple and efficient extension hinge is provided which will lie close to or be shielded within the frame and panel structure, and at the same time allow the panel to be swung to and from an open position, as well as to and from an extended position. This will allow the panel to be adjusted for the convenient washing and cleaning thereof from the inside of a building and without the necessity of reaching out through the window frame and it should be further understood that since the panel may be swung to a variety of adjusted positions, the panel or panels may be adjusted to deflect draft and to prevent the entrance of a direct draft through the window by reflecting the draft, in this way providing a ventilating means with a minimum amount of draft. It will also be seen that a simple and efficient clutching means has been provided whereby the hinge may be either used as a conventional hinge support, or by means of a slight adjustment the hinge may provide an extension hinge support to permit the supported panel to be swung to an offset position with respect to its supporting sash. The present type of hinge and particularly that type shown in Figures 1 to 14 inclusive, is especially adapted for use in conjunction with types of windows such as illustrated in Figure 1 wherein swinging panels are carried by vertically slidable sashes, this hinge structure holding the panels in a position whereby the sashes may freely slide one over the other at the same time allowing the panels to be freely swung and bodily moved inwardly with respect to the supporting frame when the sashes

are properly adjusted to permit of such movement.

Having described the invention, what I claim as new is:

1. A hinge means for connecting a panel with a sash whereby the panel may be swung away from the sash, said hinge means comprising an anchoring plate adapted to be fixed upon the sash, a hinge plate adapted to be fixed to the panel, an extension arm pivotally secured at one end to the anchoring plate, means for journaling the hinge plate upon the outer free end of said extension arm, clutch means slidably mounted upon said anchoring plate and engaging said extension arm near its pivot end for locking the extension arm against swinging movement, said clutch means comprising a slotted plate slidably mounted upon the anchoring plate, and said slotted plate and the pivoted end of said extension arm having interfitting tongue and socket connection. 15

2. As a new article of manufacture, a hinge comprising an anchoring plate, an extension arm pivotally secured at one end to the anchoring plate intermediate the ends of the anchoring plate, a hinge plate journaled upon the outer end of said extension arm and adapted to support a panel, the extension arm being foldable to an overlapping position with respect to the anchoring plate and movable to a position 25 whereby the hinge plate will be positioned beyond the anchoring plate, a sliding clutch plate carried by the anchoring plate and engageable with said extension arm for releasably locking the extension arm in overlapped position with 30 respect to the anchoring plate. 35

3. As a new article of manufacture, a hinge comprising an anchoring plate, an extension arm pivotally secured at one end to the anchoring plate intermediate the ends of the anchoring plate, a hinge plate journaled upon the outer end of said extension arm and adapted to support a panel, the extension arm being foldable to an overlapping position with respect to the anchoring plate and movable to a position 40 whereby the hinge plate will be positioned beyond the anchoring plate, a sliding clutch plate carried by the anchoring plate and engageable with said extension arm for releasably locking the extension arm in overlapped position with 45 respect to the anchoring plate, and said sliding clutch plate having a tongue and groove connection with the inner end of said extension arm. 50

4. As a new article of manufacture, a hinge comprising an anchoring plate, an extension arm pivotally secured at one end to the anchoring plate intermediate the ends of the anchoring plate, a hinge plate journaled upon the outer end of said extension arm and adapted to support a panel, the extension arm being foldable 60 to an overlapping position with respect to the anchoring plate and movable to a position whereby the hinge plate will be positioned beyond the anchoring plate, a sliding clutch plate carried by the anchoring plate and engageable 65 with said extension arm for releasably locking the extension arm in overlapped position with respect to the anchoring plate, and said anchoring plate having supporting angle brackets for facilitating the securing of the anchoring plate 70 upon one side face of a supporting sash. 75
